United States Patent

Des. 236,633
Patented Sept. 2, 1975

236,633

AQUARIUM

Samuel Shalom, 577 Grand St., New York, N.Y. 10013

Filed May 25, 1973, Ser. No. 363,950

Term of patent 14 years

Int. Cl. D30—01

U.S. Cl. D30—6

FIG. 1.

FIG. 2.

FIG. 3.

FIG. 4.

FIG. 5.

FIG. 6.

FIG. 1 is a perspective view of an aquarium showing my new design, illustrating the front and one side thereof;

FIG. 2 is a rear elevational view thereof;

FIG. 3 is a top plan view thereof;

FIG. 4 is a left side elevational view;

FIG. 5 is a right side elevational view; and

FIG. 6 is a bottom plan view thereof.

I claim:

The ornamental design for an aquarium, substantially as shown.
